UNITED STATES PATENT OFFICE.

HARRY JOSEPH HICK, OF ALLIANCE, OHIO, ASSIGNOR TO THE McCASKEY REGISTER COMPANY, (INCORPORATED IN 1914), OF ALLIANCE, OHIO, A CORPORATION OF OHIO.

FILING APPLIANCE.

1,299,573.

Specification of Letters Patent.

Patented Apr. 8, 1919.

Application filed August 10, 1916. Serial No. 114,157.

To all whom it may concern:

Be it known that I, HARRY J. HICK, a citizen of the United States, residing at Alliance, in the county of Stark and State 5 of Ohio, have invented certain new and useful Improvements in Filing Appliances, of which the following is a specification.

The invention relates to an appliance for filing sales-bills and other similar papers, 10 and is composed of a series of hinged holders, and a case in which the holders are operatively mounted, and in which they can be completely inclosed for protection against fire and like damage.

15 The improvement contemplates the use of a case or cabinet for the hinged holders, in the form of an ordinary upright fire-proof safe, in which the front wall may be composed of one or more laterally swinging 20 doors.

One object of the invention is to utilize 25 all available free space within the case or cabinet for receiving the greatest number of holders and filing the maximum number of bills; and this object is attained by mounting one bank or series of normally reclined hinged holders on a wheel carriage in the bottom of the case, and a separate bank or series of normally upright hinged 30 holders upon a carriage above the normally reclined holders; and by mechanically coördinating the two banks or series of holders so that they can be together drawn forward 35 into conveniently accessible operative position.

Further objects of the invention relate to the swinging carriage, and the oscillating back rest mounted thereon for the normally upright series of bill holders, whereby the 40 same are first carried forward into operative position, and are then counterbalanced as they are operated individually or collectively in part or as a whole; and this object of the improvement is attained by supporting the swinging carriage upon a pair of pendent links in each side of the case, and by mounting the oscillating back rest upon a pair of upright links in each side of the carriage.

45 Further objects of the invention relate to the mechanism for locking the two banks or series of bill holders in their normally inoperative position one above the other within the case or cabinet; and for coöordinating the movements of the separate series

of bill holders to and from their operative position one above and in rear of the other in front of the case or cabinet. These objects and purposes of the invention, and other ancillary advantages, are attained by 60 the construction, arrangement, and mechanism illustrated in the accompanying drawings forming part hereof, in which—

Figure 1 is a vertical section of the case with the front doors opened, and the track 65 table for the lower series of holders swung downward into operative position; showing, in side elevation in full lines, the two sets of holders in normally locked inoperative position within the case, and showing in 70 broken lines, the bill holders drawn forward into operative position at the front of the case;

Fig. 2, a fragmentary side elevation showing the locking and coördinating mechanism 75 for the two sets of holders, the lower set being drawn partway forward in position for first unlocking the mechanism and then drawing the upper set of holders forward.

Fig. 3, a fragmentary side elevation showing in full lines, all the upper holders rotated forward into reclined position above the lower set of holders, and showing in broken lines a portion of the upper set of 80 holders in normally upright position. 85

Fig. 4, a fragmentary section showing a portion of the lower set of holders rotated upward into operative position in front of and resting backward against the upper 90 set of holders.

Fig. 5, a detached perspective view of the swinging carriage, and the oscillating back rest for the upper set of holders.

Fig. 6, a plan view of the swinging carriage frame. 95

Fig. 7, a fragmentary section as on line 7—7, Figs. 5 and 6.

Fig. 8, a fragmentary section as on line 8—8, Figs. 5 and 6.

Fig. 9, a front elevation of the filing appliance showing the sides and bottom of the case in section. 100

Fig. 10, a plan view of the filing appliance showing the walls of the case in section, and part of the book shelf broken away to 105 show the top of the bill holders and connecting mechanism, and

Fig. 11, a fragmentary side elevation of the wheel carriage locked in forward operative position. 110

Similar numerals refer to similar parts throughout the drawings.

The case 1 of the filing appliance may be made of any well known fire-proof construction, with spaced wall plates, and intervening heat resisting material, and is preferably closed in front by the laterally swinging doors 2, in accordance with well known safe construction, so that the case can be 5 opened in front the entire height and width of its receiving chamber 3.

The track table 4 is hinged at 5 to the bottom of the case inside the doors 2, and is adapted to be swung into upright position 15 within the doors, or to be swung into reclined position, as shown in Fig. 1, to form a table for the lower set of bill holders 6, when the same is drawn forward into operative position, as shown by broken lines 20 in the same figure.

The upper section 4^a of the table is preferably hinged to the lower portion thereof, and is adapted to be folded under the lower section when in reclined position, and is 25 provided with the brackets 7 which form supporting legs for the table in this position. These legs are adapted to protrude within the receiving chamber of the case when the table 4 and its folded section 4^a are both 30 rotated upward on their hinges, within the doors, as shown in Fig. 10.

Triangular track bars 8 and 8^a are provided, one on each side of the bottom of the case and of the table 4, and are preferably 35 located with an upturned flange on the outer side to form guide-ways for the wheels 9 of the carriage 10, and the pivotal wheels 11 of the lower set of bill holders 6; which wheels are adapted to travel forward and 40 rearward upon the track bars.

The normally reclined bill holders 6 are connected together at their rear ends by hinges 12, and are provided with spring clips 13 on each side for receiving and holding sales bills and other like articles. The 45 pintles 14 of the pivot wheels 11 are journaled in the rear end of the bottom bill holder 6^a, and are adapted to enter and engage in the U-shaped bearings 15 secured on 50 the rear end of the carriage 10; so that the rear ends of the bill holders 6 are adapted to travel forward and rearward upon the pivot wheels 11, while the forward ends thereof rest upon the forward end of the 55 carriage, which rides upon the wheels 9; the U-shaped bearings 15 serving to hold the bill holders in proper position upon the carriage.

The frame of the carriage is shaped to 60 form the vertically presented shoulder 16 at each side and its front edge is shaped to form the rearwardly presented shoulder 17 at each side, which bottom shoulder is preferably made by forming a bead 18 on the 65 forward edge of the carriage frame, which

bead can be used as a handle for pushing or drawing the carriage in and out of the case.

The brackets 19 are secured on the forward end of the table section 4, over which brackets the bead 18 is adapted to ride when 70 the carriage is drawn forward into operative position, in which relation of the parts the shoulders 16 and 17 abut the rearward and forward sides of the bracket 19, by which abutment the carriage is stopped from forward and rearward movement while in operative position, as shown in Figs. 1, 3 and 4.

The upper normally upright bill holders 20 are connected together at their lower ends by the hinges 12^a, and are provided on each 80 side with spring clips 13^a for receiving and holding sales bills and like articles. The lower end of the foremost holder 20^a of the upper set is mounted on the transverse pivot rod 21 which rod extends through, and is 85 provided with bearings in the spaced inner and outer side plates 22 and 23; which inner plates are yoked together at the rear ends by a transverse plate 24, and constitute the frame of the swinging carriage for the 90 upper set of bill holders 20.

The back support for the upper set of bill holders comprises a U-shaped frame having the side bars 25 connected together at their rear ends by the transverse yoke bar 26, 95 which side bars 25 are pivotally supported on the upper ends of the pair of upright links 27 and 27^a on each side, the lower ends of which links are pivotally connected with the side plates 22 and 23 of the swinging 100 carriage. The forward links of each pair are preferably pivoted upon the pivot rod 21 which supports the foremost holder 20^a of the upper set.

The guide plates 28 are secured at their 105 upper ends to the rear ends of the side bars 25 of the back support. These plates extend freely downward inside the side plates 22 of the swinging carriage, and are provided with the upright guide slots 29, the lower 110 end portions 29^a of which are preferably deflected rearward. The guide slots 29 are adapted to receive the guide posts 30 extending laterally from the lower end of the rearmost holder 20^b of the upper set, so that 115 by the operation of the guide posts in the guide slots, the back support for the rearmost holder 20^b will be carried forward or rearward as one or more of the foremost holders 20 of the upper set are swung to 120 and from reclined position upon the pivoted supports; a rearward inclination of the lower end of the guide slot being preferred so that the forward movement of the following support will be deferred until after 125 several of the foremost bill holders 20 have been rotated forward in the reclined position.

It will be understood that the rearmost bill holder 20^b of the upper set normally 130

rests against and is supported by rollers 25^a which are mounted on the side bars 25 of the oscillating support and follow this holder forward and supports the same, as 5 the foremost holders are successively or collectively rotated forward into reclined position; and it is preferred to provide the supporting bracket 31 on each side of the foremost holder 20^a of the upper set, which 10 bracket is provided with the out-turned flange 31^a which is adapted to rest upon the forward end of the inner side plate 22 of the swinging carriage, for supporting the forward end of said holder 20^a when the same 15 is rotated forward into reclined position as shown in Fig. 3.

The side plates 22 and 23 on each side of the frame of the swinging carriage, are suspended on, and pivotally connected with, 20 the lower ends of the pair of pendent links 32 and 32^a, the upper ends of which links are pivoted at 33 and 33^a to the side walls of the case 1. The lower ends of the rear links 32^a of each pair may be connected with 25 the same pivot 34 which carries the lower end of the upright links 27^a, while the forward links 32 of each pair are preferably pivoted at 35 to the links 27 a substantial distance above the pivot rods 21 which carry 30 the lower ends of the links 27; so that when the upper set of links are swung forward into operative position, and especially when part or all of these holders are rotated forward into reclined position as shown in Fig. 3, the rearward inclination of the foremost 35 pendent link 32 pulling upon the foremost upright links 27 above their pivotal supports, tends to draw the follower support rearward and thereby prevents the same 40 from pushing and rotating the rearmost holder 20^b forward, which can only be done by the hand of the operator.

Locking plates 36 are pivoted to the outer side of the forward end of each side plate 45 23 of the frame of the swinging carriage, and are each provided with a curved hook 36^a adapted to engage behind the lock post 37 on the side walls of the case, for securing and locking the bill holders and their carriages in normal position within the case, as 50 is shown in full lines in Fig. 1. The lower ends of the locking plates 36 are pivoted to the forward ends of the connecting links 37^a, the rear ends of which links are pivoted to 55 the swinging controlling plates 38 which are provided with the longitudinal slots 39, and are pivoted at their upper forward ends to the pivot rod 21, at the under side of the upright links 27 between the side plates 22 and 23 of the swinging carriage frame, as 60 shown in detail in Figs. 5 and 6.

The slide posts 40 provided on each side at the rear ends of the upper bill holder 6^b of the lower set extend through and operate 65 in the longitudinal slots 39 formed in the

controlling plates 38, and by these means the locking plates are operated by a forward and rearward movement of the lower set of holder leaves upon the wheel carriage.

The longitudinal latch plate 41 is located on the outer side of each side plate 23 of the swinging table frame, which latch plates are normally held in rearward position by action of the compression springs 42 located between the L-shaped rear ends 43 of the side plates 23 and the L-shaped rear ends 44 of the latch plates 41. These springs are preferably located around the guide rods 45 extending forward from the rear end 44 of the latch plate through the guide opening 80 in the rear end 43 of the side plate 23.

The latch pins 46 are provided on the forward ends of the latch plates 41, and extend inward through the longitudinal slots 47 provided for that purpose in the side plates 85 23 of the swinging carriage frame; the length of which slots limit the longitudinal movement of the latch plates 41, the rear ends 44 of the latch plates being held by the springs 42 a short distance in rear of the 90 transverse yoke plates 24 of the swinging carriage frame, when the latch pins are at the rear ends of the slots 47, and these slots are long enough to permit the latch plates to move forward to bring their rear ends 44 95 into alignment with the yoke plates 24 forming the rear ends of the swinging carriage frame.

The upper forward end 48 of the controlling plate 38, is extended laterally and beyond the pivot bar 21, and is shaped to form the stop notch 49, which is adapted to abut the stop pin 50 secured between the side plates 22 and 23 of the swinging carriage frame, when the controlling plates 38 hang 100 directly downward as shown in Fig. 3; also to form the cam edge 51 which is adapted to impinge the latch pin 46 for moving the latch plate forward as the controlling plate swings downward and forward; and also to 110 form the latch notch 52 which receives the latch pin 46 when the controlling plate is swung forward into vertical position, as shown in Fig. 3; the latch pin being drawn rearward into the notch by action of the compression spring 42, thus locking the controlling plate in the vertical position shown in Fig. 3, whereby the lower end of the locking plate 36 is swung forward to carry the locking hook 36^a downward below the 115 locking post 37, which permits the hook to pass freely below the locking post.

The normal inoperative position of the parts is shown in full lines in Fig. 1, wherein the upper upright set of holders and its 120 supporting carriage are swung rearward into the case and are stopped from swinging forward by engagement of the hooks 36^a behind the lock posts 37; and wherein the lower reclined set of holders are shown to be 130

pushed rearward upon the track bars 8 entirely within the receiving chamber 3 of the case, so that the track table 4 and its hinged extension 4^a may be rotated upward to close 5 the front of the receiving chamber, and the doors 2 may be closed, as shown in Fig. 10.

In this relation of the parts, the free end of each controlling plate 38 is carried and held rearward and upward by engagement 10 of the slide post 40 in the longitudinal slot 39 so that this slot is located in nearly horizontal position, as shown in Fig. 1.

When it is desired to use the filing appliance, the doors 2 are swung open, and the 15 track table 4 is swung downward into reclined position, after which the operator by grasping the bead 18 on the forward edge of the wheel carriage frame, as a handle, pulls the wheel carriage and the lower set of 20 bill holders mounted thereon, forward upon the track bars.

During the first portion of this movement, the operation of the slide post 40 in the longitudinal slot of each controlling plate 38, 25 swings this plate downward and forward, first quite gradually and afterward more rapidly, until it hangs in nearly pendent position, as shown in Fig. 2; in which relation of the parts the link connection 37 with the 30 locking plate 36 rotates the hook 36^a thereof downward so as to nearly disengage the locking post 37; and the cam edge 51 on the extended end of the controlling plate 38 is swung upward into contact with the latch 35 pin 46; so that a slight forward movement of the wheel carriage and the lower set of bill holders swings the controlling plate forward into pendent position, as shown in Figs. 3 and 4; by which further movement 40 the hook 36^a of the locking plate is swung downward so that its end is clear below the lock post 37, and the cam edge 51 on the extended end 48 of the controlling plate operating on the latch pin 46, slides the latch 45 plate 41 forward until the stop notch 49 on the same end of the controlling plate abuts the stop pin 50 on the swinging frame, at which time the latch notch 52 is in position to receive the latch pin 46 which is carried 50 into the notch by action of the compression springs 42; whereupon the controlling plate is locked by the latch plate in the pendent position shown in Figs. 3 and 4, and the locking plate 36 is likewise 55 positively secured in inoperative position with its hook 36^a swung downward clear below the plane of the lock post 37.

When the lock hook 36^a is thus disengaged from the lock post 37 and the controlling 60 plate 38 is thus locked in vertical position upon the swinging frame which carries the upper set of bill holders; the further forward movement of the wheel carriage and the lower set of holders, by engagement of 65 the slide post 40 in the slot 39 of the

controlling plate 38, draws the swinging carriage and the upper set of holders forward until both sets of holders are moved forward into operative position, as shown in broken lines in Fig. 1; in which position 70 the carriages are locked against either forward or rearward movement by abutment of the shoulders 16 and 17 against corresponding parts of the bracket 19, as shown in Fig. 11 and described above. 75

When it is desired to return the bill holders into inoperative position within the receiving chamber of the case, the holders of the upper and lower sets are first swung into normally upright and reclined position respectively, as shown by broken lines 80 in Fig. 1; after which the bead 18 on the forward edge of the wheel carriage is disengaged from the abutting edge of the bracket 19, which is done by slightly lifting 85 the forward end of the carriage, and the wheel carriage is pushed rearward, which movement also carries the swinging carriage rearward by reason of the engagement of the slide post 40 in the slot 39 of the pendent 90 controlling plate 38 until the rear ends 44 of the latch plates impinge the rear wall of the case, and the further rearward movement of the swinging carriage against the action of the compression springs 45 has 95 carried the latch notches 52 rearward out of engagement with the latch pins 46; whereupon a further rearward movement of the lower set of leaves upon the wheel carriage, by action of the slide posts 40 in the slots 100 39 of the controlling plate 38, swings this plate and also the connected locking plate 36 rearward and upward, so that the hook 36^a thereon engages behind the lock post 37, thereby locking the swinging frame in 105 normal inoperative position; after which the wheel carriage and the lower set of leaves are pushed rearward into normal inoperative position within the receiving chamber of the case, as shown in full lines in Fig. 1. 110

When the two sets of bill holders are moved forward and locked into operative position, as shown by broken lines in Fig. 1, it is evident that the normal upright upper set of holders can be swung forward, 115 either singly or collectively into reclined position, as shown in Fig. 3, in which position the foremost holder 20^a is supported by the flange 31^a of the bracket 31 resting upon the forward end of the swinging frame, and the operation of the guide posts 30 in the 120 guide slots 29 carries the follower support forward, in accordance with the number of holders rotated into position, so that the rollers 25^a on the follower support are 125 always in position to form a back rest for the rearmost holder 20^b when the same is in upright position, as described above.

And likewise, when the two sets of holders are locked in forward operative position, it 130

is evident that the normally reclined lower set of holders can be swung upward either singly or collectively into upright position, as shown in Fig. 4, in which position the 5 free end of the upper holder 6^b may rest and slide upward and downward against the abutment formed by the forward face of the foremost holder 20^a of the upper set.

In this operation it is evident that the 10 weight of the upper set of holders, tending to swing rearward upon the forwardly swung pendent links 32 and 32^a, acts by the slot 39 in the controlling plate 38 upon the slide posts 40 on the rear end of the upper 15 holder 6^b, to pull this holder rearward, thereby materially assisting the upward swinging of a number of the upper holders of the lower set by counterbalancing the weight of the free ends thereof.

20 It is furthermore evident that after a considerable number of the upper holders of the lower set have been swung into upright position and the pendent links 32 and 32^a have passed vertical position, the counterbalancing effect of the weight of the upper leaves will be just reversed, so that when the lower holders of the lower set are swung into upright position, the tendency of the weight of the upper holders which have 25 already been swung into upright position, as shown in Fig. 4, to overbalance the lower holders after they are started upward and causing them to slam against the upright holders, is resisted by the tendency of the upper set of holders to swing forward upon the pendent links, thereby, to a certain extent preventing the weight of the upright holders of the lower set from overbalancing the lower holders thereof during the operation 30 from reclined into upright position and vice versa.

I claim:

1. A filing appliance including a movable carriage, a series of holders on the movable carriage, an oscillating carriage above said carriage, and a second series of holders on the oscillating carriage, the upper holders forming an abutment for the lower holders when in operative position.
2. A filing appliance including a movable carriage, a series of normally reclined holders on the movable carriage, an oscillating carriage above the reclined holders, and a series of normally upright holders on the oscillating carriage, the upper holders forming an abutment for the lower holders when in operative position.
3. A filing appliance including a movable carriage, a series of holders on the movable carriage, an oscillating carriage above said holders, a second series of holders on the oscillating carriage, and operative connections between the movable carriage and the oscillating carriage.
4. A filing appliance including a movable

carriage, a series of holders on the movable carriage, an oscillating carriage above said carriage, a second series of holders on the oscillating carriage, and means actuated by the movement of the lower carriage for moving 70 the oscillating carriage to and fro.

5. A filing appliance including a movable carriage, a series of holders on the movable carriage, an oscillating carriage above said 75 holders, a second series of holders on the oscillating carriage, and means actuated by the movement of the lower carriage for locking the oscillating carriage in a predetermined position.

6. A filing appliance including a movable carriage, a series of holders on the movable carriage, an oscillating carriage above said 80 holders, a second series of holders on the oscillating carriage, means for locking the oscillating carriage in a predetermined position, and means actuated by the movement of the lower carriage for releasing said locking means.

7. A filing appliance including a movable carriage, a series of hinged holders on the 90 movable carriage, a swinging carriage above said holders, a pendent plate on the swinging carriage, and means on one of the hinged holders in operative engagement with the pendent plate for counterbalancing the operation 95 of the holders by the oscillation of the swinging carriage.

8. A filing appliance including a movable carriage, a series of hinged holders on the movable carriage, a swinging carriage above 100 said holders, a controlling plate pivoted to the swinging carriage, means for locking the plate in pendent position, and means on one of the hinged holders in operative engagement with the controlling plate for counterbalancing the operation of the holders by the oscillation of the swinging carriage.

9. A filing appliance including a movable carriage, a series of hinged holders on the movable carriage, a swinging carriage above 110 said holders, a controlling plate pivoted to the swinging carriage having a longitudinal slot therein, means for locking the plate in pendent position, and a slide post on one of the hinged holders operating in the slot for 115 counterbalancing the operation of the holders by the oscillation of the swinging carriage.

10. A filing appliance including a movable carriage, a series of hinged holders on 120 the carriage, a swinging carriage above said holders, a second series of hinged holders and a pendent plate on the swinging carriage, and means on one of the hinged holders in operative engagement with the pendent plate for counterbalancing the operation 125 of the lower holders by the weight of the upper holders on the swinging carriage.

11. A filing appliance including a movable carriage, a series of hinged holders on the 130

movable carriage, a swinging carriage above said holders, a second series of hinged holders on the swinging carriage, a controlling plate pivoted to the second carriage, means 5 for locking the plate in pendent position, and means on one of the lower holders in operative engagement with the controlling plate for counterbalancing the operation of the lower holders by the weight of the upper 10 holders on the swinging carriage.

12. A filing appliance including a movable carriage, a series of hinged holders on the movable carriage, a swinging carriage above said holders, a second series of hinged holders 15 on the swinging carriage, a controlling plate pivoted to the swinging carriage having a longitudinal slot therein, means for locking the plate in pendent position, and a slide post on one of the lower holders operating 20 in the slot for counter-balancing the operation of the lower holders by the weight of the upper holders on the swinging carriage.

13. A filing appliance including a movable carriage, a series of hinged holders on the movable carriage, an oscillating carriage above said holders, a controlling plate and a connected locking plate pivoted to the oscillating carriage, and means on the lower 30 carriage engaging the controlling plate for operating the locking plate by the movement of the lower carriage.

14. A filing appliance including a support, a series of normally upright holders hinged 35 together and pivotally mounted by the foremost holder upon the support, upright links pivoted on the support, a pendent supporting follower for the rearmost holder pivoted on the upright links, and means on one 40 of the holders in operative engagement with the follower.

15. A filing appliance including a support, a series of normally upright holders hinged together and pivotally mounted by the foremost holder upon the support, upright links pivoted on the support, a supporting follower for the rearmost holder pivoted on the upright links, pendent plates on the follower frame, and means on one of the holders in 45 operative engagement with the pendent plates.

16. A filing appliance including a support, a series of normally upright holders hinged together and pivotally mounted by 50 the foremost holder upon the support, upright links pivoted on the support, a follower frame pivoted on the upright links, pendent plates on the follower frame, means on one of the holders in operative engagement with the pendent plates, and means on 55 the follower frame for supporting the rearmost holder in upright position.

17. A filing appliance including a support, a series of normally upright holders 60 hinged together and pivotally mounted by

the foremost holder upon the support, a pair of upright links pivoted to the support on each side of the holders, a follower frame pivoted on the upright links, pendent plates on the follower frame, means on one of the 70 holders in operative engagement with the pendent plates, and means on the follower frame for supporting the rearmost holder in upright position.

18. A filing appliance including an oscillating carriage, a series of normally upright holders hinged together and pivotally mounted by the foremost holder upon the carriage, upright links pivoted on the carriage, a follower support frame for the rearmost holder pivoted on the links, guide plates depending from the follower frame having 75 guide slots therein, and pins on the rearmost holder operating in the guide slot.

19. A filing appliance including an oscillating carriage, a series of normally upright holders hinged together and pivotally mounted by the foremost holder upon the carriage, upright links pivoted on the carriage, a follower frame pivoted on the links, 80 guide plates depending from the follower frame having guide slots therein, pins on one of the holders operating in the guide 85 slots, and means on the follower frame for supporting the rearmost holder in upright 90 position.

20. A filing appliance including an oscillating carriage, a series of normally upright holders hinged together and pivotally mounted by the foremost holder upon the carriage, upright links pivoted on the carriage, a follower supporting frame for the rearmost holder pivoted on the links, guide plates depending from the follower frame having 95 guide slots therein, pins on one of the 100 holders operating in the guide slots, the lower portion of the guide slots being inclined rearward.

21. A filing appliance including a carriage, a series of normally upright holders 110 hinged together and pivotally mounted by the foremost holder upon the carriage, a pair of upright links pivoted on each side of the carriage, a supporting follower for the rearmost holder pivoted on the upright 115 links, and a pair of pendent links on each side of the carriage having pivotal connections therewith, one of the pendent links of each pair being pivoted to the corresponding upright link above its pivotal connection 120 with the carriage.

22. A filing appliance including a movable carriage, a series of holders on the movable carriage, an oscillating carriage above said holders, a second series of holders on the oscillating carriage, means for locking the oscillating carriage in a predetermined position including a controlling plate pivoted to the carriage, means on the carriage for stopping the controlling plate in lock- 125 130

ing position, a latch plate on the carriage normally protruding in rear of the same and having a latch pin in the path of the controlling plate, there being a cam edge on the controlling plate for impinging the latch pin and moving the latch plate forward when the controlling plate rotates into locking position and a notch in the controlling plate for receiving the latch pin for stopping the controlling plate in locking position.

23. A filing appliance including a movable carriage, a series of holders on the movable carriage, an oscillating carriage above said holders, a second series of holders on the oscillating carriage, means for locking the oscillating carriage in a predetermined position including a controlling plate piv-

oted to the carriage, means on the carriage for stopping the controlling plate in locking position, a latch plate on the carriage normally protruding in rear of the same and having a latch pin in the path of the controlling plate, there being a cam edge on the controlling plate for impinging the latch pin and moving the latch plate forward when the controlling plate rotates into locking position and a notch in the controlling plate for receiving the latch pin for stopping the controlling plate in locking position and a notch in the controlling plate for receiving the latch pin for stopping the controlling plate in locking position, and there being an abutment at the rear end of the latch plate for disengaging the latch pin from the notch when the oscillating carriage is swung rearward.
